UNITED STATES PATENT OFFICE.

FRANK RHIND, OF MERIDEN, ASSIGNOR TO THE BRIDGEPORT BRASS COMPANY, OF BRIDGEPORT, CONNECTICUT.

DESIGN FOR A BICYCLE-LANTERN.

SPECIFICATION forming part of Design No. 23,582, dated August 21, 1894.

Application filed July 5, 1894. Serial No. 516,660. Term of patent 14 years.

To all whom it may concern:

Be it known that I, FRANK RHIND, a citizen of the United States, residing at Meriden, in the county of New Haven and State of Connecticut, have invented and produced a new and original Design for Bicycle-Lanterns; and I do declare the following to be a full, clear, and exact description of the same, reference being had to the accompanying drawings, forming a part thereof.

Figure 1 is a plan view; Fig. 2 a side elevation, and Fig. 3 is an inverted plan view.

The leading features of my design consists in the general configuration and ornamentation of the lantern, substantially as herein-after described.

1 denotes the case which is provided at top and bottom with ornamental beads 2; 3 the reservoir, the sides of which incline down-

ward and outward in a slightly concave curve, 20 and which is provided with ornamental beads 4 at top and bottom, and on its under side with ribs or corrugations 5; 6 an open-work connection between the case and the reservoir; 7 the cone reflector which is provided 25 with an ornamental bead 8, and 9 the top which is provided with ornamental beads 10, and the upper surface of which is provided with ornamental ribs 11.

I claim—

The design for a bicycle lantern substantially as herein shown and described.

In testimony whereof I affix my signature in presence of two witnesses.

FRANK RHIND.
